UNITED STATES PATENT OFFICE.

CHARLES I. HOOPLE, OF OAKLAND, CALIFORNIA.

CONNECTING MEANS FOR FABRIC STRIPS.

1,227,053.

Specification of Letters Patent. Patented May 22, 1917.

Application filed May 12, 1915. Serial No. 27,552.

To all whom it may concern:

Be it known that I, CHARLES I. HOOPLE, a citizen of the United States, residing at Oakland, in the county of Alameda and 5 State of California, have invented new and useful Improvements in Connecting Means for Fabric Strips, of which the following is a specification.

This invention relates to connecting means 10 for fabric strips, and pertains more particularly to a means for connecting a pair of tie ends to a celluloid or other central band section.

The objects of the invention are to provide 15 a connecting means which will effectively hold the tie ends to the central band and which will enable the tie to slip more easily around the collar to allow of convenient adjustment of the tie.

20 Further, the invention aims to provide a connecting means which is of finished and attractive appearance devoid of projections or sharp edges likely to catch or prove otherwise objectionable, and to also provide a 25 finishing strip or member which completely conceals and is auxiliary to the primary connector.

The invention consists of the parts and the 30 construction and combination of parts as hereinafter more fully described and claimed, having reference to the accompanying drawings, in which—

Figure 1 is a plan view of the tie.

Fig. 2 is an enlarged, detail view of one 35 end of the tie, showing the clenching strip in position.

Fig. 3 is a view similar to Fig. 2 showing the finishing band applied.

Fig. 4 is a perspective view of the clench- 40 ing strip.

Fig. 5 is a perspective view of the finish- 45 ing band.

Fig. 6 is a section on line 6—6 of Fig. 3.

A indicates a band section constructed of 45 thin, flexible material, such as celluloid, or the like, and 2 and 3 a pair of tie ends secured thereto. The band section is adapted to fit between the sections of a turn-down collar and its length is slightly less than 50 the length of the collar. It is thus entirely concealed while the projecting fabric ends are free to be tied together to form a bow knot or tie of any desired shape.

One of the important features of the pres-

ent invention is the manner in which the tie 55 or fabric ends are secured to the band section. This is accomplished as follows: The end of the band is first inserted between the fabric ends 4 of the tie. A metal clenching strip 5 provided with prongs 6, is then forced 60 through the fabric and band and clenched over, thus securing the band and fabric section together. A finishing strip, such as indicated at 7, is then folded around the joint formed by the band and fabric exteriorly 65 of the clenching strip 5, thus covering the clenching strip and the ends of the prongs and at the same time forming a finish at the joint or connection between the band and fabric. The tie as a whole is then placed in 70 a suitable form of press where the edges 8 and 9 of the finishing strip are forced down against the band and fabric to further clamp or secure the two sections together. The 75 corners of the finishing strip are then slightly indented, as indicated at 10, to round or destroy any points which might otherwise be formed, and also for the purpose of forcing the material of the finishing strip into the band A and fabric 4, thus further securing the several sections together and also preventing the finishing strip from opening up.

A tie constructed as here shown can be very cheaply manufactured as it requires less 85 than $\frac{1}{2}$ of the material employed in common ties now in use. The securing clips formed by the clenching strip and finishing strip 7 does not only form a positive, strong securing means between the band and fabric ends, 90 but also produces an ornamental finish at this point which should materially promote the sale and appearance of the tie.

The connecting band between the tie ends 95 constructed of celluloid or like flexible material together with the securing clips, is very thin and consumes such a small space between the sections of a turn-down collar that the tie can be pulled or slipped around the collar with practically no resistance, thus permitting the tie to be quickly adjusted with relation to the front collar button even where the closest type of turn-down collar is worn.

Having thus described my invention, what I claim and desire to secure by Letters Patent is—

A device for connecting overlapping parts, including a clenching strip for securing the

parts together, and a finishing strip formed independent of the clenching strip and having two sides and ends encircling said parts and disposed over the clenching strip, said finishing strip being of greater width than that of the clenching strip and having each of its four side edges bent inwardly toward said parts and over the side edges of the clenching strip so as to completely conceal 5 the latter and to secure the two parts to- 10

gether, said finishing strip extending over the points of overlapping of said parts so as to completely conceal said points.

In testimony whereof I have hereunto set my hand in the presence of two subscribing 15 witnesses.

CHARLES I. HOOPLE.
